UNITED STATES PATENT OFFICE

2,453,016

GRAIN ELEVATOR AND TREATING APPARATUS

Edwin T. Johnson and Albin E. Johnson,
Walcott, N. Dak.

Application October 4, 1945, Serial No. 620,330

3 Claims. (Cl. 259—22)

1

This invention relates to a grain elevator and treating apparatus, and more particularly to such a device adapted for the loading and unloading of grain, and the simultaneous treatment thereof with poison for the extermination of vermin therein.

A primary object of this invention is to elevate and treat grain simultaneously in an improved manner.

A further object of the invention is to drive the elevator and the poison disseminating or treating means simultaneously from a single source of power. Among its features, the invention is characterized by a poison container mounted on the conveyor shaft of the grain elevator, and operable by the driving power for said elevator simultaneously with the actuation thereof.

A further feature of the invention resides in the provision of adjustable means whereby the angle of inclination of the elevator may be varied at the will of the operator.

An additional important feature of the invention resides in the provision of an improved container for poison or other treating material and means in the container for agitating and disseminating the material contained therein, as well as controlling the admission thereof to the grain.

A further feature resides in the provision of an attachment for the elevator whereby grain may either be loaded directly from a bin, or may be loaded by the bushel, when it is desired to measure the same prior to loading.

Other features will in part be obvious and in part be pointed out as the description of the invention proceeds and shown in the accompanying drawing wherein there is disclosed a preferred embodiment of this inventive concept.

In the drawings:

Figure 1 is a side elevational view, partially broken away, of one form of elevator and treating device embodying features of the instant inventive concept.

Figure 2 is a top plan view of a portion of the structure shown in Figure 1 taken substantially along the line 2—2 of Figure 1.

Figure 3 is an elongated longitudinal sectional view, partially broken away, taken substantially along a longitudinal center line of the device shown in Figure 1.

Figure 4 is a sectional view taken substantially along the line 4—4 of Figure 3 as viewed in the direction indicated by the arrows.

Figure 5 is a sectional view taken substantially along the line 5—5 of Figure 3, as viewed in the

2

direction indicated by the arrows, certain parts thereof being shown in a different position of adjustment.

Figure 6 is an end elevational view of the device shown in Figure 1 taken substantially along the line 6—6 as viewed in the direction indicated by the arrows.

Figure 7 is an end elevational view of the opposite end of the device shown in Figure 1 taken substantially along the line 7—7 in the direction indicated by the arrows.

Figure 8 is an enlarged sectional view taken substantially along the line 8—8 of Figure 1 as viewed in the direction indicated by the arrows.

Figure 9 is a top plan view of an attachment for the device.

Figure 10 is a sectional view taken substantially along the line 10—10 of Figure 9, and

Figure 11 is an end elevational view of the device shown in Figure 10 taken substantially along the line 11—11 as viewed in the direction indicated by the arrows.

Similar reference characters refer to similar parts throughout the several views of the drawings.

Having reference now to the drawings, and more particularly to Figure 1, there is generally indicated at 15 a tubular chute, one end of which is elevated as by an elevating bracket 16, to be more fully described hereinafter, and the elevated end of which is provided with a discharge opening 17, and an end cap 18. The lower end of the sleeve 15 is open, and has secured thereto extending numbers 19 supporting an end cap 20 a spaced distance from the open end of the sleeve 15.

Suitably journaled in end caps 18 and 20 are the extremities of a rotatable shaft 21 surrounded by a helical feed screw 22. The upper end of the shaft 21 carries a drive pulley 23, driven by means of a V-belt 24 which is in turn driven by a pulley 25 carried by the drive shaft 26 of an electric motor 27, or the like, preferably carried on a frame, generally indicated at 28, secured to the sleeve 15. From the foregoing, it will now be seen that the feed screw 22 when rotated by the belt 24 is adapted to move grain from the inlet at the open end of the sleeve 15 upwardly to the outlet 17, to discharge the same into any desired locality, as, for example, a storage bin, a truck body, or the like.

The shaft 21 exteriorly of the end cap 18 carries a pulley 29 which drives through a V-belt 30 a pulley 31 mounted on the extremity

of the shaft 32 supported by mounting brackets 33 on the upper side of the sleeve 15. The shaft 32 terminates in a bevel gear 34 at a point adjacent the lower extremity of the sleeve 15, the bevel gear 34 being adapted to mesh with a bevel gear 35 carried by a vertical shaft 36 which extends upwardly within a cylindrical container or receptacle 37, suitably secured as at 38 to one of the brackets 33. The receptacle 37 is provided with a lid 37a and is adapted to contain a poison or similar material for treatment of the grain carried by the elevator.

A spider 39 provided with a central bearing 40 serves as a journal for the upper extremity of the shaft 36, which shaft is provided with a plurality of agitator fingers 41. The receptacle 37 is provided with a discharge tube 42, which opens into an aligned offset portion 43 of the sleeve 15, positioned directly above the helical feed screw 22. It will now be seen that when the elevator is in operation, the shaft 36 is driven through the gears 34 and 35 from the shaft 21, and the agitating fingers 41 thoroughly stir up the poison or other material in the receptacle 37 and permit the same to pass downwardly through the spout 42 and the opening 43 for admixture with the grain being conveyed by the feed screw 22.

Means are provided for controlling the flow of poison or the like into the spout 42 and take the form of a slide plate 44 mounted in the slide-way 45 positioned adjacent the opening of the spout 42. The position of the slide 44 may be fixed either in open position as shown in Figure 5, or in closed position as shown in Figure 4, by means of a set screw 46 suitably mounted in the slide-way 45.

Referring back to the mounting bracket 16, it will be seen, as best shown in Figure 8, that the bracket comprises a U-shaped member including legs 50 and a base 51, the legs 50 being secured as by pins 52 in pivotal relation to the sides of the sleeve 15. The base 51 is pivotally mounted on a pivot 53 on a plate 54 provided at its extremities with flange plates 55 provided with clamping screws 56 to enable the same to be secured to a prop 57 or the like, as best shown in Figure 1.

Thus it will be seen that pivotal motion exists with respect to the mounting bracket and the sleeve 15, as well as the rotatable movement of the sleeve within the bracket about the fixed support 57, whereby the elevator may be relatively moved to various positions in the grain bin and raised or lowered at its open or lower end, as may be desired or necessitated by the condition and relative position of the grain.

Under certain conditions, it is desired that grain be fed, as from bushel baskets or the like, to the elevator, and not picked directly from the bin by the elevator. An attachment, as best shown in Figures 9, 10, and 11 is provided for this purpose, and takes the form of a tubular

member 60 partially opened at its top to form a hopper 61 in the form of an inverted truncated pyramid, and open at its bottom to permit grain positioned therein to fall to the bottom of the tubular member 60, where it may be engaged by the helical feed screw 22. Set screws 61 are provided about the peripheral rim of the tubular member 60 to permit the same to be held in position on the sleeve 15.

From the foregoing, it will now be seen that there is herein provided an improved grain elevator and treating device which accomplishes all of the objects of this invention, and others, including many advantages of great practical utility and commercial importance.

As many embodiments may be made of this inventive concept, and as many modifications may be made in the embodiment hereinbefore shown and described, it is to be understood that all matter herein is to be interpreted merely as illustrative and not in a limiting sense.

We claim:

1. A grain elevator and treating apparatus comprising an inclined sleeve having inlet and outlet openings therein, a helical feed screw in said sleeve, a container for treating material mounted on said sleeve, a passage connecting said container with said sleeve, an agitator in said container, means for rotating said screw, a lay shaft mounted upon said sleeve and connected with said feed screw adjacent said means, and gearing positioned between the base of said container and said sleeve for connecting said lay shaft and said agitator, said sleeve being open at its lower end to constitute said inlet, a bearing for said feed screw positioned externally of said inlet end and an open-sided support cage for securing said bearing to said sleeve.

2. The combination of claim 1 including a hopper, a delivery tube extending from the lower portion of said hopper, and means for clamping said tube upon said support cage.

3. The combination of claim 2 including communicating means connecting said hopper with said inlet including registering openings in said tubes and cage.

EDWIN T. JOHNSON.
ALBIN E. JOHNSON.
